UNITED STATES PATENT OFFICE.

CHARLES ALGERNON PARSONS, OF NEWCASTLE-UPON-TYNE, ENGLAND.

FLUID-PRESSURE TURBINE.

972,908.

Specification of Letters Patent. Patented Oct. 18, 1910.

Application filed December 18, 1909. Serial No. 533,747.

To all whom it may concern:

Be it known that I, CHARLES ALGERNON PARSONS, a subject of the King of Great Britain and Ireland, and residing at Heaton Works, Newcastle-upon-Tyne, in the county of Northumberland, England, have invented certain new and useful Improvements Relating to Fluid-Pressure Turbines, of which the following is a specification.

10 This invention relates to turbines of the type in which the working fluid is expanded in a number of segmental jets formed by radially restricting the space between the turbine rotor and casing at intervals along 15 the length of the turbine, the kinetic energy of the fluid being subsequently absorbed in moving blades carried by the rotor and placed between adjacent sets of restrictions.

The invention consists in providing in a 20 turbine of the above type a plurality of guide blades placed in said restrictions, which blades are adapted to convey the steam in an axial direction while imparting velocity to it, the steam being then given 25 circumferential direction without substantial change of velocity before delivery to blading of the velocity absorption type whereby the energy of the steam is abstracted.

30 It is desirable that the space between the rotating and fixed member shall be restricted on about the mean diameter of the space to form such an annular jet or such segmental jets at several intervals in the length so as 35 to divide the turbine into a series of pressure stages each stage having one or more rows of guide and rotating blades upon which the steam from the preceding restriction impinges. In order to obtain the best 40 results the number of rows of blades per stage should be small. The restriction is made such that the width of the jet delivered by it is less than the height of the blades following said restriction by which 45 means very little or no clearance losses can occur.

In the accompanying drawings which illustrate diagrammatically several ways of carrying out the invention. Figures 1 and 50 2 are part elevation and plan respectively of one arrangement of the restrictions and guide blades in a turbine according to the present invention. Figs. 3 and 4 are views

of a similar turbine in which the working fluid after passing guides in the barrier flows through two rings of rotating blades with a row of guide blades between them. Figs. 5 and 6 are views corresponding to Figs. 3 and 4 showing a slightly modified configuration of barrier, and with 60 the height of the blades increasing gradually through each stage.

In carrying the invention into effect according to the construction shown diagrammatically in the above figures a series of annular restrictions, a , a^1 , a^2 , are provided in the turbine. Each restriction may be formed by a barrier strip, d , secured to the casing e , opposite to a similar strip, f , secured in a groove in the turbine drum or 70 spindle, g . The adjacent faces of these strips leave an annular space of such a form as to allow for an expansion of the working fluid to occur. From the first restriction or barrier, a , the working fluid passes through 75 a ring of guide blades, b , followed by rotating blades, c , from which the steam is passed through another annular jet, a^1 , of slightly larger area and is further expanded to impart suitable velocity for the next stage 80 which may consist of fixed and moving blades, this action being repeated as many times as desired through the turbine.

As shown in Figs. 1 and 2 the first row of guide blades b have their leading edges 85 extending through the annular jet, the guide blades, b , being formed with extensions, h , passing through the barrier but formed with a clearance space at j , in order to avoid undue resistance by the front edges of the 90 blades cutting the fluid issuing from the barrier. The extensions, h , may be formed with sharpened or narrowed leading edges, k , as shown at the barriers, a^1 and a^2 , in the plan view of Fig. 2. It will be understood 95 of course that the arrangements of the blades, although only a single row of rotating blades, c , is shown, when the guides extend through the barrier may be of any convenient number and character. For example more than two rows of blades may be placed abaft the annular jet restrictions the first row being rotating blades of the Parsons' type then a row of crescent shaped blading which directs the fluid into another 105 row of moving blades of crescent form.

If the form of the barrier strips is such that the desired expansion of the steam is not effected until the steam has passed nearly to the right hand side of the barrier strips, the portions, *h*, of the guide blades, *b*, which pass between the barrier strips are made parallel so that the steam is directed in a straight, as distinguished from a curved, course all the time that the expansion is taking place in the jet or restriction. In some cases however, the barrier may be formed so that the full expansion for the chosen difference of pressure between the pressure on the left of the barrier and that on the right thereof shall take place in the first part of the barrier and that no expansion shall occur in the remaining part of it. The guide blades are secured to the barrier strip, *d*, the parts of the blades in the expansion part of the barrier or jet being formed parallel or substantially parallel to the axis of rotation, the curved guiding portion of the blade being in the remaining part of the barrier. The free ends of these guide blades are formed to follow with the usual clearance the curved contour of the rotating barrier strip. By this means loss by spilling is further reduced. Two forms of turbine in which this formation is adopted are shown in Figs. 3-6.

In Figs. 3 and 4 the desired nozzle formation is obtained mainly by the curvature of the rotating part of the barrier; or as in Figs. 5 and 6 by the curvature of both parts of the barrier. The guide blades which are of the whole width of the fixed barrier part extend close to the opposite rotating part of the barrier. The parts of the guide blades to the left of a line B-B in Fig. 4 (which marks approximately the part of the jet where expansion for the chosen pressure drop is complete) are formed so that the mean direction of the fluid is kept in a straight path but the parts to the right of that line where the pressure, cross section and velocity are approximately constant are much more curved or bent to guide the fluid in the proper direction for the working blades *c*. As the ends of the blades follow the curvature of the rotating part of the barrier any fluid that may spill from one blade at the clearance space over the barrier part, *f*, is caught by the next blade and properly directed. The ends of the blades should correspond as closely as possible to the contour of the barrier, only the usual working clearances being provided.

It is intended that in all forms the height of the blades shall be greater than the width of the jet delivered by the restriction, and to allow for the widening of the jet after leaving the barrier, the height of the blades may be gradually increased through each stage as shown in Fig. 5.

It will be obvious that the invention may be embodied in many forms; in all forms the pressure drop is confined mainly or wholly to the annular openings or barriers between the fixed and moving members of the turbine, and the annular or segmental openings are on a circle of approximately the mean diameter of the space between the rotor and casing.

When the jets are of segmental form the part of the circumference between the jet is occupied by suitable baffles.

If the turbine be of the single flow type the usual dummy piston leakage will occur but if it be constructed with two equal turbines with working fluid flowing in opposite directions practically no leakage will occur, because the dummies may be dispensed with.

It is obvious that in the above described arrangements the functions of the cylinder and spindle blading are generally speaking interchangeable.

Having now described my invention what I claim as new and desire to secure by Letters Patent is:—

1. A turbine having fixed and rotating parts, the space between which is restricted radially to form jets at intervals along the length of the turbine and guide blades extending through said restrictions.

2. A turbine having fixed and rotating parts, the space between which is restricted radially to form jets at a plurality of intervals along the length of the turbine and guide blades extending through said restrictions, these guide blades giving a circumferential direction to the working fluid after having been expanded in said restrictions.

3. A turbine having fixed and rotating parts the space between which is restricted radially to form jets at intervals along the length of the turbine and guide blades placed within said restrictions and carried by one of said parts whereby the steam is expanded in flowing axially through said restrictions and is then given a circumferential direction by said blades.

4. A turbine having in combination fixed and moving parts, the space between which is restricted radially to form jets at intervals along the length of the turbine, guide blades in said restriction carried by one of said parts, said blades being arranged to convey the working fluid axially during expansion of the same and then acting to give a circumferential direction thereto, and means carried by said turbine parts for absorbing the velocity of the working fluid thus generated when passing through said restrictions.

5. A turbine having in combination fixed and moving parts, the space between which is restricted radially to form jets at inter-

- vals along the length of the turbine, guide blades in said restriction carried by one of said parts, said blades being arranged to convey the working fluid axially during expansion of the same and then acting to give a circumferential direction thereto, and means carried by said turbine parts for absorbing the velocity of the working fluid thus generated when passing through said 5 restriction, said velocity absorbing means giving a gradually increasing cross sectional area for the passage of the working fluid between adjacent restrictions.
6. A turbine having in combination fixed and moving parts, the space between which is restricted to form jets at intervals along the length of the turbine, guide blades in said restriction carried by one of said parts, and blades being arranged to convey the 10 working fluid axially during expansion of the same and then acting to give a circumferential direction thereto, alternating rows of rotating and guide blades following said 15 restrictions whereby the velocity of the fluid generated in passing through said restrictions is absorbed.
7. A turbine having in combination fixed and moving parts, the space between which is restricted radially to form jets at intervals along the length of the turbine, guide blades in said restriction carried by one of said parts, said blades being arranged to convey the working fluid axially during expansion of the same and then acting to give a 20 circumferential direction thereto, alternating rows of rotating and guide blades following said 25 restrictions whereby the velocity of the fluid generated in passing through said restrictions is absorbed, said blades giving a gradually enlarging cross sectional area for the passage of the working fluid between adjacent restrictions.
8. A turbine having fixed and moving parts, the space between which is restricted 45 radially to form jets at intervals along the length of the turbine, guide blades placed in said restriction and carried by the fixed turbine part, alternate rows of moving and fixed blades following said restriction so 50 that velocity is imparted to the moving turbine part.
9. A turbine having fixed and moving parts, the space between which is restricted radially to form jets at intervals along the 55 length of the turbine, guide blades placed in said restriction and carried by the fixed turbine part, alternate rows of moving and fixed blades following said restriction so 60 that velocity is imparted to the moving turbine part, said fluid and moving blades giving a gradually increasing cross sectional area for the passage of fluid between the adjacent restrictions.
10. In combination in an elastic fluid tur- 65 bine, a casing and rotor moving therein, the space between the rotor and casing being restricted radially so as to form jets at intervals along the length of the turbine, guiding means placed within said restriction and imparting angular direction to the working 70 fluid only after it has been expanded in said restrictions and means intermediate between said restrictions for absorbing the velocity of the expanded fluid.
11. In combination in an elastic fluid tur- 75 bine a casing and a rotor moving therein, the space between the rotor and casing being restricted radially so as to form jets at intervals along the length of the turbine, guiding means placed within said restriction and imparting angular direction to the working 80 fluid and means intermediate between said restrictions for absorbing the velocity of the expanded fluid, said means giving a gradually increasing cross sectional 85 area for the passage of the working fluid.
12. A turbine having moving and fixed parts the space between which is radially restricted to form jets at intervals along the length of the turbine, guide blades carried 90 by the fixed turbine part and extending within said restrictions while having the contour of the restriction forming part of the moving turbine part.
13. A turbine having moving and fixed 95 parts the space between which is radially restricted to form jets at intervals along the length of the turbine, guide blades extending through said restriction, the blades and parts forming the restrictions being formed 100 so as to provide passages which give a circumferential direction of flow to the working fluid without any change of cross section in the guide blade passages following the restriction. 105
14. A turbine having moving and fixed parts, a barrier strip carried by the former and a barrier strip removably attached to the fixed turbine part, guide blades attached to the fixed barrier strip and following the 110 contour of the moving barrier strip.
15. A turbine having moving and fixed parts, a barrier strip carried by the former and a barrier strip removably attached to the fixed turbine part, guide blades attached 115 to the fixed barrier strip and following the contour of the moving barrier strip, said guide blades giving circumferential direction to the working fluid without any change in the velocity thereof. 120
16. A turbine having moving and fixed parts, a barrier strip carried by the former and a barrier strip removably attached to the fixed turbine part, guide blades attached to the fixed barrier strip and following the 125 contour of the moving barrier strip, said guide blades giving circumferential direction to the working fluid without any

change in the velocity thereof, two rows of Parsons' blades carried by the moving turbine part and a row of crescent guide blades between the two rows of moving blades whereby the working fluid leaving said restrictions has the velocity which it has generated therein absorbed in the rotating blades before passing to the next restriction.

In testimony whereof, I affix my signature in presence of two witnesses.

CHARLES ALGERNON PARSONS.
